DESIGN FOR A LENS STRAP FOR RIMLESS SPECTACLES

Henry W. Grom and Charles J. Eagle, Rochester,
N. Y., assignors to Arcraft Optical Co., Rochester, N. Y.

Application November 12, 1934, Serial No. 53,992

Term of patent 14 years

To all whom it may concern:

Be it known that we, Henry W. Grom and Charles J. Eagle, citizens of the United States, residing at Rochester, in the county of Monroe and State of New York, have invented a new, original, and ornamental Design for Lens Strap for Rimless Spectacles, of which the following is a specification, reference being had to the accompanying drawing, forming a part thereof.

Figure 1 is a front elevation of a lens strap showing our new design.

Figure 2 is an end elevation of the same.

Figure 3 is a top plan view thereof.

We claim:

The ornamental design for a lens strap for rimless spectacles, as shown.

HENRY W. GROM.
CHARLES J. EAGLE.
